HIS ATTORNEY.

UNITED STATES PATENT OFFICE.

WILLIAM HENRY HOLBROOK, SR., OF VENICE, ILLINOIS.

NAIL.

1,276,764.

specification of Letters Patent. Patented Aug. 27, 1918.

Application filed October 26, 1916. Serial No. 127,740.

To all whom it may concern:

Be it known that I, WILLIAM H. HOLBROOK, Sr., a citizen of the United States, residing at Venice, in the county of Madison and State of Illinois, have invented certain new and useful Improvements in Nails, of which the following is a specification.

This invention relates to certain new and useful improvements in nails, the peculiarities of which will be hereinafter described in the specification and particularly pointed out in the claim.

The object of my invention is to provide a style of nail that is adapted to serve the usual purpose of a nail but in addition thereto may be readily removed and used repeatedly, thereby rendering it especially applicable for use in scaffolding or other construction of a more or less temporary character.

In the accompanying drawing on which like reference letters indicate corresponding parts,

Figure 1 is a side elevation of the main body portion of a nail constructed in accordance with the present invention.

Fig. 2 is a similar view with the supplemental head member in place, the main body portion of the nail being shown in dotted lines.

Fig. 3 is a side elevation of a slightly modified form of supplemental head member, and

Fig. 4 is a transverse section on the line $a-a$ of the construction illustrated in Fig. 3.

Referring to the drawings, wherein like reference characters designate corresponding parts throughout the several views, 2 designates the body portion of the nail preferably constructed of round wire. The body portion 2 is suitably pointed at one end and at its opposite end is provided with an integral head 3.

4 designates a supplemental head member adapted to fit over the body of the nail with one end thereof engaging the under face of the integral head 3 to form a shoulder below said integral head 3.

The supplemental head 4 is provided with a reduced portion or neck 5 intermediate its ends to provide for the engagement of the claw of a hammer or other drawing means beneath the integral head 3 for withdrawing the nail. The outer end face of the supplemental head member is adapted to act compressively on the wood or other material

into which the nail is driven home, in the same manner as the head of an ordinary nail but said supplemental head member 4 performs the additional function of maintaining the integral head 3 in a slightly raised position from the surface of the wood or other material, to permit the engagement of a claw hammer or similar tool therewith so that the nail can be readily withdrawn.

The body portion 2 of the head is provided with an exteriorly disposed angularly faced part 6 adjacent the integral head 3, and the supplemental head member 4 has a body part receiving opening extending centrally and longitudinally thereof and of a size and shape corresponding to the shape in cross section of the angularly faced portion 6 of the body part, the supplemental head member 4 being adapted to fit upon the angularly faced portion of the body part 2 with one end face fitting against the under face of the integral head 3. The reduced portion or neck 5 of the supplemental head member 4 has an angularly shaped outer face for the engagement of the claw or other drawing tool, this construction providing for turning and loosening of the nail in the withdrawing operation.

In Figs. 3 and 4 of the drawing is illustrated a slightly modified form of supplemental head member. The construction illustrated in these figures is the same however as that shown in Fig. 2, with the exception that in this instance the supplemental head member has enlarged portions at both ends thereof instead of only at its lower end as in the construction Figs. 1 and 2.

For temporary houses for camps of working crews, and for scaffolding, concrete forms, and other construction, that are subject to more than one erection and removal, my style of nail tends to avoid splitting and waste of lumber and other material with which it is used, lessens the labor of wrecking, and reduces the cost of constructions.

Having thus fully described my invention, what I claim as new, and desire to secure by Letters Patent, is:

A nail comprising a body part provided at one end with a head formed integrally therewith and having an angularly faced portion adjacent said head, in combination with a separately formed supplemental head member adapted to be detachably engaged with said body part, the supplemental head

member being provided with a body part receiving opening extending centrally and longitudinally thereof and of a size and shape corresponding to the shape in cross section of the angularly faced portion of the body part, said supplemental head member being adapted to fit upon the angularly faced portion with one end face fitting against the under face of the integral head, the other end face of the supplemental head member constituting a work engaging shoulder at a point below the integral head, said

supplemental head member intermediate its ends being reduced in thickness and shaped to provide an exteriorly disposed angularly 15 faced claw engaging portion with shoulders at opposite ends thereof.

In testimony whereof I have affixed my signature in presence of two witnesses.

WILLIAM HENRY HOLBROOK, Sr.
